DESIGN FOR A HEAD FOR INTERNAL COMBUSTION ENGINE BREATHER SYSTEM

Adolph C. Dressler, Miami, Okla., assignor to Dieselair Corporation, Miami, Okla., a corporation of Delaware

Application August 7, 1939, Serial No. 86,498

Term of patent 14 years

To all whom it may concern:

Be it known that I, Adolph C. Dressler, a citizen of the United States, residing at Miami, in the county of Ottawa and State of Oklahoma, have invented a new, original, and ornamental Design for a Head for Internal Combustion Engine Breather System, of which the following is a specification, reference being had to the accompanying drawing, forming a part thereof.

Fig. 1 is a perspective view of the head for

internal combustion engine breather system showing my new design.

Fig. 2 is a top plan view thereof.

Fig. 3 is a side elevational view thereof; and Fig. 4 is an end elevational view thereof.

I claim:

The ornamental design for a head for internal combustion engine breather system, as shown.

ADOLPH C. DRESSLER.
